CHARLES W. WHEELER, OF EAST SYRACUSE, NEW YORK, AND PAUL WILLIS, OF CHICAGO, ILLINOIS, ASSIGNORS TO C-S ENGINEERING COMPANY, OF ENGLEWOOD, NEW JERSEY, A CORPORATION OF DELAWARE

LOCOMOTIVE TANK

Application filed May 7, 1930. Serial No. 450,570.

This invention relates to fluid supply tanks and more particularly to locomotive water tanks, whether carried on the locomotive or on the usual tender therefor, and we have 55 herein illustrated the invention as applied to a locomotive tender.

It is, of course, desirable in railway operation, to reduce to a minimum the number of stops required for a locomotive to take on 60 water, and this is especially so with modern motive power and with up-to-date operating practices, which tend toward longer locomotive runs and a minimum number of stops, both in passenger and freight service. In the 65 past, it has been the practice to provide track pans or troughs along level stretches of the right of way and scoops on the locomotive tenders for taking water while in motion, in order to avoid stopping and starting trains at 70 regular water stations. More recently, especially with the advent of heavier motive power, which has of itself necessitated heavier bridges and right of way generally, larger and heavier tenders of greater water carrying 75 capacity have been provided.

Such equipment is expensive, and in addition, particularly as to the water troughs and scoops, requires considerable attention for maintenance as well as to prevent the troughs 80 from freezing up in winter, and even in spite of this additional outlay and maintenance expense, the problem is not fully met by the use of either one or both of these expedients, primarily for the reason that, although there 85 may theoretically be sufficient water in a large size tender tank to run past one or more filling stations or track troughs or possibly to arrive at the next terminal, yet, in practice, unscheduled stops must be made before reaching 90 the desired destination, or even in some cases locomotives must be changed since the entire supply of water in the tender tank is not really available, because of the low level 95 of the water in the tender (which is spread out over a relatively large area of the tender water bottom) or because it cannot be counted upon to give an even flow to the injector or water pump on account of surging of the 100 water backward and forward which causes

uncovering of the outlet pipe and breaking of the suction.

In view of the foregoing, our invention, in its broad aspect, contemplates the extension of locomotive runs beyond the distances heretofore possible, the elimination of heretofore necessary water stops, the supplementation of the effectiveness of present water supply equipment, and in some cases the entire obviation of the necessity for maintaining track pans, and even the avoidance of the necessity of providing additional water supply facilities or employing larger tenders.

In general, the invention involves the provision of means for utilizing to the full or making fully available, the supply of liquid contained in a movable liquid supply tank, such as a locomotive tender, and more specifically the utilization of the movements of the tank itself to accomplish this end.

In attaining the foregoing, we contemplate the provision of means for maintaining a head of water over the tank outlet, even at times when the general average liquid level in the tank has become very low, and in the preferred embodiment of the invention as applied to a locomotive tender tank, we propose to divide the tank into a plurality of sections and to maintain, even when the total supply of water in the tank is small, a level of water in the section from which the outlet pipe leads which will make possible the utilization of practically all the water in the tank, and we further contemplate the provision of a simple, easily maintained, inexpensive, positive and automatic device for obtaining this end, preferably actuated by or under the influence of the movement or surging of the water caused by the movements of the tank.

More specifically, we contemplate the division of a movable tank, such as a tender tank, into a plurality of sections or chambers, from one of which the supply outlet or suction pipe leads; and to provide a device, such as a flap-valve (operable by gravity or by the pressure of the water or by both), which will open in a direction to permit a flow of water, as it surges in the tank, into the suction-pipe-equipped chamber from the

other chamber or chambers, but not the reverse, so as to build up or maintain a head of water on the suction pipe especially at times when the total water supply in the tender 5 is running low; and in addition to this we contemplate the use of mechanical means for assisting the valve device in its operation and obviating undue slamming thereof, and means for preventing clogging of or interference with the valve means, as by foreign 10 matter introduced into the tank with the water.

How the foregoing objects and advantages, together with such others as are incident to 15 the invention or will occur to those skilled in the art, are attained, will be evident from the following description, taken together with the accompanying drawings, in which drawings,

20 Figure 1 is a longitudinal, vertical section through a locomotive tender tank, taken on the line 1—1 of Figure 2, showing one embodiment of our invention; and

25 Figure 2 is a transverse section through the tender tank, on line 2—2 of Figure 1.

By reference to the drawings, it will be seen that we have illustrated a locomotive tender tank 2 having the usual suction pipe or water supply outlet 3, which is generally 30 located at the forward end of the tender, as shown. Such tanks are ordinarily supplied with swash-plates to prevent excessive surging of the water, and also sometimes employed to serve as braces or stiffeners for the tank 35 itself. We segregate the portion of the water for a section of the tank adjacent the outlet 3, as indicated at 4, by means of a partition wall or plate 5, forming chambers 4 and 6, and it should be understood that the plate 40 5 may be a separate plate built into the tank for this purpose or may be one of the usual swash-plates extended downwardly to form a complete partition or division wall, such plate, in any case, preferably extending transversely of the tender tank.

Communication between the sections of the tank is provided by means of one or more openings 7 in plate 5 (three being here shown), preferably located at or very near 50 the bottom thereof. Any suitable means, such as a pivoted gate, cover, or valve 8, tending to close by gravity and by water pressure, and acted upon by a yielding device such as springs 9, (which here serve also as 55 the pivot means), may be employed to close each opening 7, such means being arranged to open only in one direction, that is in a direction to admit water from chamber 6 to chamber 4, under the influence of a forward 60 surge of the water in the tank, as when the brakes of the vehicle are applied or when it is inclined on a grade, and to restrict or entirely prevent the movement of water in the opposite direction, as when the vehicle 65 gives a rearward surge to the water.

The action of the device is, therefore, in the nature of a flap-valve or check-valve action, to effect an automatic intermittent flow of water in one direction only, or substantially in one direction, to wit: from the rear chamber 6 to the forward chamber 4, so that when the water level in the tender is low, as indicated at 6a, there will still be maintained, almost until the complete exhaustion 70 of the water supply, an available head or level of water above the outlet pipe 3 as indicated at 4a. In this connection it will be understood that excessive rise of the water in chamber 4, or overflow through the vent 10 thereof, will not occur, since the force of the surging water is not sufficient to raise a head of water in chamber 4 to the top thereof under any ordinary conditions of service, but to make this absolutely certain, the pressure of the 80 springs 9 may be so arranged or adjusted that only a sufficient head of water will be maintained in chamber 4 to ensure constant supply for outlet 3 up until the time when the total supply is practically exhausted.

To prevent interference with the action 85 of the valves, as by dirt or foreign matter present in the water introduced into chamber 6 through the filling throat 11, we provide a filter or screen 12, interposed between 90 partition 5 and throat 11.

By virtue of the usual sloping coal floor 13, positioned between the side portions or legs 14 of the tank, the capacity of chamber 4 is, of course, materially less in proportion 100 to its length than the capacity of chamber 6, which tends to augment the desired effect, that is to provide an increased head of water in chamber 4 per unit volume of water forced thereinto, and in this connection we may add 105 that the advantages obtainable by the invention may be still further enhanced by placing the partition 5 farther forward, for example at a point adjacent the juncture 15 of the sloping sheet 13 with the floor sheet 16.

From the foregoing, it is believed to be 110 evident that the desired objects are obtained in a simple and efficient manner, and by a device which is inexpensive to apply either to existing or new equipment, which is automatic in its action, requires little or no attention or maintenance, utilizes forces which are normally available in service and which 115 ordinarily serve no useful purpose, and involves no application of outside power or energy and no complicated apparatus. In short, it will be seen that in normal operation the engine crew can actually utilize practically all the water in the tender, which has not heretofore been possible; and it is even conceivable that, as a last resort in exceptional circumstances where the water is very 120 low, the engineer could disconnect the locomotive from the train, run it ahead a short distance and stop suddenly to bring practically 125 the last gallon of water into the front com- 130

partment and enable him to reach his terminal.

What we claim is:—

1. A divided tender tank having an inlet in one section thereof and an outlet in another section, means permitting flow of water from the former section to the latter and constructed to restrict opposite flow, and dirt-intercepting means between said last-named means and said inlet. 5

2. A fluid container for railroad vehicles having two compartments divided by an upright partition, an opening in the partition near the bottom thereof for passage of fluid in a substantially horizontal direction, and means permitting flow of fluid from one compartment into the other but constructed to restrain flow in the opposite direction. 15

3. A fluid container for railroad vehicles having two compartments divided by an upright partition, an inlet to one compartment, an outlet from the other compartment, an opening in the partition near the bottom thereof for passage of fluid in a substantially horizontal direction, and a check valve therefor opening toward the compartment having the outlet under the influence of surging due to the motion of the locomotive. 25

4. A fluid container for railroad vehicles having two compartments divided by an upright partition, an inlet to one compartment, an outlet from the other compartment, an opening in the partition near the bottom thereof for passage of fluid in a substantially horizontal direction, and a check valve therefor opening toward the compartment having the outlet under the influence of surging due to the motion of the locomotive, together with dirt-intercepting means between the inlet and said check valve. 35

5. A fluid container for railroad vehicles having two compartments divided by an upright partition, an inlet to one compartment, an outlet from the other compartment, an opening in the partition near the bottom thereof for passage of fluid in a substantially horizontal direction, and a flap valve therefor mounted upon a spring member which urges the valve to closed position, said flap valve being arranged to open to permit flow from the compartment having the inlet to the compartment having the outlet under the influence of surging due to the motion of the locomotive. 45

6. A fluid container for railroad vehicles having two compartments divided by an upright partition, an inlet to one compartment, an outlet from the other compartment, an opening in the partition near the bottom thereof for passage of fluid in a substantially horizontal direction, and a flap valve therefor mounted upon a spring member which urges the valve to closed position, said flap valve being arranged to open to permit flow from the compartment having the inlet to 55

the compartment having the outlet under the influence of surging due to the motion of the locomotive, together with dirt-intercepting means between the inlet and said flap valve. 70

7. A locomotive water tank of greater length than width with the longer dimension arranged lengthwise of the locomotive, a transverse partition dividing the tank into two compartments, a water inlet to one compartment, a water outlet from the other compartment, an opening in the partition near the bottom thereof, and a check valve therefor opening toward the compartment having the outlet under the influence of surging due to the motion of the locomotive. 75 80

In testimony whereof, we have hereunto signed our names.
